UNITED STATES PATENT OFFICE

159,664

GARMENT HANGER

Percy R. Pontious, Castro Valley, Calif.

Application March 28, 1949, Serial No. 1,666

Term of patent 7 years

(Cl. D33—8)

To all whom it may concern:

Be it known that I, Percy R. Pontious, a citizen of the United States of America, residing at Castro Valley, in the county of Alameda and State of California, have invented a new, original, and ornamental Design for a Garment Hanger, of which the following is a specification, reference being had to the accompanying drawing, forming a part thereof.

Fig. 1 is a side elevational view of a garment hanger showing my new design.

Fig. 2 is a front elevational view of the same.

Fig. 3 is a top plan view of the garment hanger, and

Fig. 4 is a bottom plan view of the same.

I claim:

The ornamental design for a garment hanger, substantially as shown.

PERCY R. PONTIOUS.
